Attorneys

Patented May 27, 1924.

UNITED STATES PATENT OFFICE.

CHARLES MACK, OF ST. PAUL, MINNESOTA.

LUGGAGE CARRIER.

Application filed November 5, 1921. Serial No. 513,145.

To all whom it may concern:

Be it known that I, CHARLES MACK, a citizen of the United States, residing at St. Paul, in the county of Ramsey and State of Minnesota, have invented a new and useful 5 Luggage Carrier, of which the following is a specification.

My invention relates to improvements in luggage carriers.

10 Its object is to provide a simple, durable and inexpensive device of this kind including removable running board clamps and carrier frames, one frame being detachably supported by the clamps and the second 15 frame detachably supported by the first frame in two relations, whereby said second frame may be carried in extended position for use or carried in overlapping relation with respect to the first frame, when its use 20 is not required.

With the foregoing and other objects in view, which will appear in the following description, the invention resides in the novel combination and arrangement of parts and 25 in the details of construction hereinafter described and claimed.

In the drawings, Fig. 1 is a side elevation of a device embodying my invention, the same being illustrated in extended form and 30 applied to a vehicle running board; Fig. 2 is a perspective view in detail of one of the running board clamps; Fig. 3 is a similar view of one of the posts of the bottom carrier frame; Fig. 4 is a perspective view in 35 detail of one of the posts of the top carrier frame and Fig. 5 is a vertical sectional view taken through co-operating posts and clamp of the carrier, the top frame thereof being shown in position of disuse.

40 Referring to the drawings, I have used the reference letter A to indicate the running board clamps and B and C to designate respectively the bottom and top carrier frames.

The clamps A are identical, each comprising 45 a body 10 with upper and lower arms 11 and 12, said body being provided with reversely turned clips 13 forming a tapered socket 14 and the lower arm supplied with a winged clamping screw 15 threaded therein. 50 Two or more of these clamps A may be employed, the same being readily applied to and removed from a running board as clearly shown in Fig. 5. The bottom frame B is made up of posts 16, one for each clamp, 55 and rails 17 welded, riveted or otherwise secured to said posts. The lower end of each

post 16 is tapered, as at 18, to fit the socket 14 of its respective clamp, the upper end of the post being supplied with reversed clips 19 forming a tapered socket 20 similar to the 60 sockets 14 on the clamps A. The top carrier frame C comprises posts 21, one for each post 16 of the bottom frame B, and rails 22 suitably secured to said posts 21. The lower ends of the posts 21 are tapered as at 23, to 65 fit the sockets 20 in the bottom frame B, while the upper extremities of said posts 21 are turned outward and downward, the depending tips 24 being tapered to correspond with the lower tapered ends 23. 70

To accommodate a bulky load, the clamps A are applied to a running board, the ends 18 of the posts 16 seated in the sockets 14 in said clamps and the ends 23 of the posts 21 seated in the sockets 20 in the posts 16. The 75 tapered joints between the top and bottom frames and between the bottom frame and clamps rigidly hold the parts together, without rattling, yet permit the carrier structure to be quickly and easily dismantled. The 80 bottom frame B may be lifted from the clamps A and put aside, when the use of the carrier is abandoned, the clamps in this instance being removed from or left upon the running board as may be desired. The 85 clamps upon a running board are not unsightly, and occupying but little space may well be left undisturbed, particularly when the disuse of the carrier is temporary. The 90 entire reach of a carrier of the present capacity is at times unnecessary. Under such circumstances, the top frame C may be lowered to position substantially within the 95 confines of the bottom frame B (Fig. 5), the tapered tips 24 being fitted in the sockets 20 in the posts 16. 100

Changes in the specific form of my invention, as herein disclosed, may be made within the scope of what is claimed without departing from the spirit of my invention.

I claim—

1. In a device of the class described, a plurality of clamps for attachment to a vehicle running board, said clamps being formed with tapered post receiving sockets, a bottom carrier frame including posts having tapered lower ends to fit the sockets in said clamps and formed at their upper ends with tapered post receiving sockets, a top carrier frame including posts tapered at their lower ends 105 to fit said last mentioned sockets, the upper ends of said posts being turned outward and 110

downward, the downward turned portions thereof being tapered to fit said last mentioned sockets.

2. In a device of the class described, a bottom carrier frame for attachment to a vehicle running board, said frame including posts having sockets at the upper ends thereof, a top frame including posts, the lower ends thereof fitting the sockets of the posts in the bottom frame and depending members on the upper ends of said posts in said top frame to fit said sockets.

3. In a device of the class described, a plurality of clamps for attachment to a vehicle

running board, each clamp having an upright socket therein, a bottom carrier frame including posts, one for each clamp, the lower ends of said posts being tapered to fit the sockets in said clamps and the upper ends thereof formed with post receiving sockets, and a top carrier frame including posts, the lower ends thereof being tapered to fit in the sockets in the posts of the bottom frame.

In testimony whereof, I have signed my name to this specification.

CHARLES MACK.
